UNITED STATES PATENT OFFICE

WILLIAM RODERICK BARCLAY, OF LEICESTER, ENGLAND, ASSIGNOR TO UNITED SHOE MACHINERY CORPORATION, OF PATERSON, NEW JERSEY, A CORPORATION OF NEW JERSEY

SHOE SUPPORT

Application filed September 9, 1925, Serial No. 55,321, and in Great Britain October 6, 1924.

This invention relates to shoe-supports, and is illustrated as embodied in a jack designed to be employed in a machine for attaching heels by nails driven from the inside of the shoes.

It is difficult, with the somewhat convex metal tops of jacks often employed in the attachment of heels from the insides of shoes, to secure proper distribution of the working 10 clamping pressure over the heel-seat portion of a shoe, so that the heel-seat on the sole shall be properly forced into contact with the cupped end of a heel and the various nails or other fastenings fully driven, and at the same time to avoid so localizing the pressure upon the margin or other portion of the seat of a heel of wood or similar material that said heel shall not be broken. It is an object of the 15 present invention to guard against this difficulty.

In the attainment of this object, as a feature of my invention, there is provided a shoe-support having tubes for receiving nails or other fastenings, about which tubes is a body arranged for contact with the heel-seat portion of a shoe, said body and tubes being organized for relative movement under pressure of the work and offering to the shoe, when under the influence of such pressure, 20 substantial uniformity of contact and reaction over the entire area. This body is preferably capable of conforming to the contour of the heel-seat portion, being of such yieldable material as rubber. Because of the capacity of the contacting body for adapting itself to the opposing surface of the work, the stresses set up in the heels being attached are equalized and their fracture is avoided. 25 As illustrated, the contact-surface of the yieldable material lies outside the ends of the nail-tubes. This permits the body, under the working pressure, to occupy a surface substantially identical with that in which 30 the ends of the tubes are situated, thus giving more complete continuity of engagement with the work.

This and other features and the various objects of the invention will be made apparent in the following description of a particu-

lar form of my improved support shown in the accompanying drawing, in which:

Fig. 1 is a partial side elevation of said support taken on the line 1—1 of Fig. 2; and

Fig. 2 is a top plan view of the support.

At 10 appears the body-portion of my improved jack or shoe-support, in which is a series of vertical openings 12, here shown as five in number, arranged in accordance with the nailing design which it is desired to employ. Seated in counterbored upper ends of the openings are nail-tubes 13, shown as in two vertical sections, they being thus divided to enable them more readily to be formed to receive nails of such a type as those known as shovel-headed. Each pair of tube sections is surrounded by a sleeve 14 retaining the two portions assembled, this sleeve having at its lower end a flange 16 resting upon the top of the body-portion 10. The sleeves pass through openings in a retaining plate 18, overhanging the flanges 16 and held in place upon the jack by one or more screws 20. In the tubes operate drivers 22 carried by a head 24, formed upon the upper extremity of a spindle 26 arranged to reciprocate in a vertical passage through the jack. The spindle may be actuated in any convenient manner, the driving means not being shown. Carried within a recess in the upper portion of the jack and contacting at its lower end with the head 24 is a spring 28 acting to hold the drivers normally depressed.

Covering the top of the jack, overlying the plate 18 and surrounding the tubes 13 is a body of yieldable material, which may be furnished by a pad 30 of rubber. The pad is shown as practically continuous, being broken only by openings 32 which the nail-tubes fit closely. It is somewhat thicker than the length of the tubes above the plate 18. The general contour of the upper surface of the pad, or that with which the heel-seat portion of a shoe operated upon contacts, approximates that of such heel-seat portion, 95 resembling in this respect the usual metal jack-top.

A shoe being in place upon the jack with the heel-seat surface of the insole resting upon the pad 30, and a heel to be attached

engaging the heel-seat, pressure is applied to the work, as is customary, to hold the heel firmly in place. This is to prepare it to receive the inserting force of the nails which have been placed in the tubes 13 and are carried upon the ends of the drivers. The 5 nails are driven by the elevation of the spindle 26 when the machine in which the jack is used is started. The clamping pressure necessary to prevent displacement of the heel is considerable, and if a jack-top of non-compressible material, as iron, is employed, the lack of identity between the contours of the contact-surface of the jack and the varying forms of the cupped ends of wood or other frangible heels which are to be 10 nailed throws unevenly distributed stresses upon the heels, as they are forced against the heel-seats. Commonly because of the desire 15 to obtain a tight crease, the excess of pressure is marginal, leaving the centers of the heels inadequately supported. However this may be, the lack of uniform support is likely to 20 result in the breakage of many heels. With 25 the present arrangement, as the pressure is applied, the pad 30 yields and adjusts itself both vertically and laterally, the work-engaging surface being depressed until, through a proper selection as to the compressibility of the material constituting a 30 pad, it approximately coincides with a surface in which lie the upper extremities of the tubes 13, and there is substantial uniformity of contact and reaction over the entire area. 35 In this way the clamping force imposed upon the heels is equalized and danger of breaking them is slight.

Having described the invention, what I 40 claim as new and desire to secure by Letters Patent of the United States is:

1. A shoe-support comprising fastening-receiving tubes, and a body surrounding the tubes and arranged for contact with the heel-seat portion of a shoe, said body and tubes 45 being organized for relative movement under pressure of the work and offering to the shoe under the influence of such pressure substantial uniformity of contact and reaction over the entire area.
2. A shoe-support comprising fastening-receiving tubes, and a body co-operating with the tubes and arranged for contact with the heel-seat portion of a shoe, said body being capable of conforming under pressure 50 to the contour of said heel-seat portion.
3. A shoe-support comprising fastening-receiving tubes, and yieldable material surrounding the tubes and arranged to furnish a shoe-supporting surface.
4. A shoe-support comprising fastening-receiving tubes, and a body surrounding the tubes and having a surface arranged for contact with a shoe and movable under working 55 pressure into substantial coincidence with a surface in which lie the ends of the tubes.

5. A shoe-support comprising fastening-receiving tubes, and yieldable material surrounding the tubes and having a surface lying outside the ends of said tubes and arranged for contact with the heel-seat portion 70 of a shoe.

6. In a jack for heel-attaching machines, a body-portion, nail-tubes projecting therefrom and being spaced from one another, drivers operating in the tubes, and a pad filling the space between the projecting ends of the tubes. 75

7. In a jack for heel-attaching machines, a body-portion, nail-tubes projecting therefrom and being spaced from one another, 80 drivers operating in the tubes, and a rubber pad seated between the tubes and having a surface lying outside the ends of said tubes and arranged for contact with the heel-seat portion of a shoe. 85

In testimony whereof I have signed my name to this specification.

WILLIAM RODERICK BARCLAY.
